United States Patent Office

Des. 191,665
Patented Oct. 31, 1961

191,665

MOTOR TRUCK

Theodore Ornas, Jr., and Charles B. McGrew, Jr., Fort Wayne, Ind., assignors to International Harvester Company, Chicago, Ill., a corporation of New Jersey

Filed Feb. 9, 1961, Ser. No. 63,878

Term of patent 7 years

(Cl. D14—3)

FIG. 1.

FIG. 2.

FIG.3.

The dominant features of our design reside in the portions shown in full line.

We claim:

The ornamental design for a motor truck, substantially as shown and described.
